DEVICE FOR DETECTING AND RETRIEVING SUNKEN LOGS

Meredith W. Chatten, Long Beach, Calif., assignor to
Franks Dredging Company, Long Beach, Calif., a part-

Application April 20, 1953, Serial No. 349,925

4 Claims. (Cl. 294—66)

My invention relates generally to the field of dredging, and more particularly to a device for detecting and retrieving logs lying at the bottom of a body of water.

A dredge, as is well known, is employed in the removal of bulk material from the bottom of a body of water. One form of dredge removes such material by means of the hydraulic action of a circulating current of water, where-in water is circulated at a velocity sufficient to pick up bulk material at the desired rate and direct it into the mouth of the dredge for subsequent disposal.

Dredging is frequently carried out on stationary bodies of water that have previously been used in logging operations. During logging operations, a certain percentage of the logs floated on the water sink before reaching their destination, and when the type of dredge above described works on such waters used for logging, these sunken logs present a most troublesome problem. Unless the sunken logs are removed, they are carried up into the mouth of the dredge, together with other bulk material, to obstruct the mouth passage of the dredge. However, removal of such sunken logs prior to the dredging operation is by no means simple. Normally waters on which logs are floated during logging operations are stationary and relatively shallow. Over a period of years, such bodies of water become jet black due to the tannic acid dissolved from the logs. Thus it is impossible to see sunken logs from above the surface of the water, despite the fact that they may lie only two or three feet below the surface thereof.

The primary purpose in devising my present invention is to provide a device that may be utilized to detect the position of sunken logs, as well as to retrieve same, irrespective of the size of the logs.

A major object of my invention is to provide a sunken log detecting and retrieving device of simple mechanical structure that may be easily manipulated by a single man, and one that is capable of functioning equally well in shallow water, as well as in water of relatively great depth.

Another object of my invention is to supply a device that is compact, of sturdy construction, easily portable, and may be fabricated from standard commercially available materials at a relatively low cost.

A further object of my invention is to furnish a device that is positive in operation, and one that permits the detection and recovery of sunken logs with the expenditure of a minimum of time and effort.

These and other objects and advantages of my invention will become apparent from the following description of a preferred form thereof, and from the drawing illustrating that form in which:

Figure 1 is a perspective view of my invention when in use to detect sunken logs;

Figure 2 is a perspective view of a sunken log as it is being retrieved after detection;

Figure 3 is a side elevational view of my invention;

Figure 4 is a vertical cross-sectional view of the device;

Figure 5 is a vertical cross-sectional view of the lower

portion of the device, showing the spring compressed for ejecting the pointed log-retrieving member therefrom; and,

Figure 6 is a perspective view of the trigger mechanism employed in actuating my invention.

Referring now to the drawings for the general arrangement of my invention, it will be seen that it is of tubular construction, and includes an elongated log-engaging member L removably supported in a guide G by a hand line C. Guide G also functions as a probe in locating the position of logs under the surface of the water, as will later be explained in detail.

My invention includes a trigger mechanism T, which when actuated, permits a compressed spring S to expand and forcibly move an ejector E downwardly into guide G. Downward movement of ejector E permits the log-engaging member L to be directed into a sunken log, and spring S may be returned to its compressed position by means of a mechanism M.

My invention also includes an intermediately positioned tubular member 10 that supports guide G on its lower end portion. A tubular member 11, used principally as a handle, is mounted on the upwardly disposed end of member 10, and the lower end of member 11 is situated within member 10, providing a circular seat 11a for the upper end of spring S to abut against, as may best be seen in Figure 4. The upper end of guide G is positioned within the tubular member 11 to provide an annular stop 12.

Tubular members 10 and 11 are held together as an integral unit by a transversely disposed bolt 13. Guide G is affixed to tubular member 10 by spot welding, or the like, located at position 10a. Ejector E includes a shaft 14 that is slidably mounted in guide G, and shaft 14 has an annular head 15 mounted on the upper end thereof, of which head is disposed within the confines of tubular member 10. The upper face 15a of the head is at all times in contact with the lower end 16 of spring S. Spring S is of the helical type, the upper end 17 of which abuts against the seat 11a. Head 15 may move longitudinally in tubular member 10, with the degree of upward movement thereof being determined by the compression on spring S. Downward movement of head 15 is limited by the downwardly disposed face 15b thereof coming into contact with stop 12.

The spring-compressing mechanism M includes a bracket 19 mounted on tubular member 10, which bracket is provided with a transversely disposed pin 20 that pivotally supports an elongated lever 21. A light chain 22 extends downwardly from one end of the lever 21, and has an L-shaped hook 23 mounted on the free end thereof. A longitudinally disposed slot 24 is formed in tubular member 10 that extends upwardly from the lower edge thereof, which slot is of such width as to slidably receive a substantially horizontal leg 23a forming a portion of hook 23. Leg 23a extends inwardly into tubular member 10 a distance sufficient to removably engage the lower face 15b of the ejector head. With the head 15 so engaged, the lever 21 may be rotated to draw the hook upwardly, and upward movement of head 15 and hook 23 results in compression of the spring S.

Spring S is normally maintained under compression by the trigger mechanism T. In Figures 4 and 6 it will be seen that the trigger mechanism includes an outwardly projecting lug 27 that supports a transversely disposed pin 28. A substantially E-shaped plate 29 formed from a rigid sheet metal material is supported at approximately the center thereof by the pin 28. Member 29 includes an upwardly disposed substantially horizontal leg 30, and a somewhat longer downwardly disposed leg 31.

The outer end portion of the longer leg 31 projects through a slot 32 formed in the tubular member 10, and may engage the under face 15b of the ejector head. The

3

head-engaging edge portion 33 of leg 31 is so tapered that the spring-loaded head tends to cause clockwise rotation of the plate 29. However, such rotation is prevented by the outwardly disposed end of leg 30 when it contacts the outer face of a bar 34 of a substantially rectangular cross section. The bar 34 is pivotally supported on a pin 35, and in Figure 6 it may be seen that a pin 35 is fixedly supported on tubular member 10 by a U-shaped mounting 36. Mounting 36 may be welded or otherwise affixed to tubular member 10.

The log-engaging member L embodies an elongated shaft 40 having a pointed lower end 41, and is in effect a spear. A fin 42 formed of sheet metal extends outwardly from the shaft 40 and is of such thickness as to be slidably in a longitudinally extending slot 43 formed in the lower portion of the guide G. An opening 44 is formed in fin 42 through which the lower end of line C passes to be permanently affixed to the log-engaging member in a conventional manner.

The operation of my invention is extremely simple. Logs which have sunken to the floor of a body of water are located by first using my invention as a probe. As the guide G is moved about under the surface of the water W, it comes into contact with a sunken log, generally designated 50, whereby further movement of the device in a particular direction is prevented. By movement of my invention, while at the same time keeping the lower end of guide G thereof in contact with the sunken log, the approximate diameter of the log may be easily determined. A sunken log discovered by such a probing operation may be engaged by member L by placing the lower end of guide G against the exterior of the log at substantially the mid-point of its diameter and pulling upwardly on a light chain 51 such as copper sash chain, the lower end of which is attached to the outer end of bar 34, causing the inwardly disposed end portion of bar 34 to move downwardly to the extent that it no longer contacts the extremity of leg 30. The spring loading on head 15 causes the E-shaped plate 29 (as shown in Figure 4) to pivot in a clockwise direction, to release head 15.

As spring S expands, the ejector E is moved downwardly to cause the log-engaging member L to be disengaged from guide G with sufficient force that shaft 40 is charged from guide G with sufficient force that shaft 40 enters log 50, as shown in Figure 2. At the time the log is engaged by shaft 40, the lower end of guide G is in contact therewith. Shaft portion 41 is formed with spirals 41a for log-engaging purposes. After the extremity 41 of shaft 40 is embedded in log 50, the log may be brought to the water surface by the exertion of upward force on hand line C. The force exerted on line C to raise the log to the surface is normally relatively light, due to the slight differential in specific gravity of the sunken log from that of water. Shaft 40 of member L, as may best be seen in Figure 4, is disposed within the confines of guide G, but has a fin 42 that projects through slot 43. When the operator of the device holds the line C taut, the member L will be maintained in guide G until discharged therefrom by ejector E.

Shaft 40 may be removed from the log 50 after it has been retrieved and the shaft replaced in guide G (Figure 2) with the fin 42 slidably mounted in slot 43. Hook 23 is then placed in groove 24, with leg 23a engaging the under face of head 15. By manually rotating the lever 21 (Figure 4) in a counterclockwise direction, the ejector E is drawn upwardly until the leg 31 engages the under face of head 15. Bar 34 may then be pivoted by use of cable 51 to the position shown in Figure 6, in which position the spring loading on head 15 cannot cause movement of E-shaped plate 29. My invention is then ready for use once again in locating and retrieving another sunken log.

In dredging operations, a workman equipped with my invention usually operates in a small boat a considerable distance ahead of the dredge. After the sunken logs are

raised to the water surface, they are moved to a suitable location by conventional means. While not necessary, it is desirable to have more than one line C and log-retrieving member L in operation so that the probing for sunken logs may continue during the time a log is being retrieved and brought to the surface.

Although my invention as above described is fully capable of achieving the objects and providing the advantages hereinbefore mentioned, it is to be understood that it is merely illustrative of a preferred embodiment of my invention, and that I do not mean to be limited to the details of construction herein shown other than as defined by the appended claims.

I claim:

15. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; a trigger pivotally supported on said guide, said trigger having a leg that may be so positioned to extend through an opening formed in said guide to removably engage said head and hold same in fixed position; trigger actuating means extending upwardly from said trigger from a position above the surface of the water in which said guide is submerged; a helical spring that is at all times in compression and disposed in said tube, the upper end of which spring occupies a fixed position therein with the lower end thereof movably engaging said head, said lower spring end being adapted to assume either a first position where said trigger engages said head or a second position where said head is in contact with said stop; and a line extending upwardly from said fin to a position above said water surface, which line when taut holds said member completely within the confines of said guide to prevent entanglement of said member with underwater vegetation when said guide is employed as a probe, with said line when slack serving as means to raise a sunken log to the water surface after said member is caused to engage same by placing the lower guide end in contact with said log, actuating said trigger to release said ejector and permit said spring to discharge said member into said log.
20. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
25. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
30. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
35. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
40. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
45. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
50. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
55. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
60. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
65. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
70. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit
75. A device for detecting and retrieving sunken logs, which includes: a rigid tube; an elongate log-engaging member formed with an outwardly projecting fin; a tubular guide coaxially mounted on the lower end portion of said tube and forming a stop at the junction therewith, which guide is adapted to slidably receive said member, with said fin projecting through a longitudinal slot formed in said guide when said member is so received; an ejector slidably mounted in said tube and guide, which ejector is provided with a head that is at all times disposed in said tube and limits the extent of downward movement of said ejector by contacting said stop; trigger means that removably engage said head to hold it in fixed position; means for actuating said trigger from above the surface of the water in which said guide is submerged; spring means that are at all times in compression and in engagement with said head, which means are under maximum compression when said head is engaged by said trigger means and under lesser compression when said head is in contact with said stop; and a line extending upwardly from said fin to a position above said water surface, which line when taut retains said member in a fully shielded position within the confines of said guide until such time as said trigger is actuated to permit

expansion of said spring means causing said ejector to discharge said member into a sunken log.

3. A device as defined in claim 2 provided with a lever pivotally mounted on said tube, which lever supports a hook therefrom adapted to be inserted through a longitudinal opening formed in said tube and removably engage said head when it is in contact with said stop, causing said head to move upwardly into engagement with said trigger means, which upward movement of said head results in the return of said spring means to its maximum compressed condition. 10

4. A device as defined in claim 2, the log-engaging member of which is formed with a threaded pointed lower end portion adapted to securely engage a sunken log when discharged thereinto.
